Primary Examiner — Rhea Shields(74) *Attorney, Agent, or Firm* — Michael Best & Friedrich LLP(57) **CLAIM**

We claim the ornamental design for an X-ray aiming ring, as shown and described.

DESCRIPTION

FIG. 1 is a perspective view of an X-ray aiming ring embodying the invention.

FIG. 2 is a front view of the X-ray aiming ring of FIG. 1. FIG. 3 is a first side view of the X-ray aiming ring of FIG. 1.

FIG. 4 is a second side view of the X-ray aiming ring of FIG. 1.

FIG. 5 is a top view of the X-ray aiming ring of FIG. 1; and, FIG. 6 is a bottom view of the X-ray aiming ring of FIG. 1. The dash-dot lines illustrate boundaries of the claimed design. Portions of the X-ray aiming ring shown in broken lines form no part of the claimed design.
